UNITED STATES PATENT OFFICE.

ARTHUR REGINALD ANGUS, OF MINEHEAD, ENGLAND.

RAILWAY SAFE-RUNNING DEVICE.

1,417,016.

Specification of Letters Patent. Patented May 23, 1922.

Application filed February 10, 1912. Serial No. 676,891.

(GRANTED UNDER THE PROVISIONS OF THE ACT OF MARCH 3, 1921, 41 STAT. L., 1313.)

To all whom it may concern:

Be it known that I, ARTHUR REGINALD ANGUS, a subject of the King of Great Britain and Ireland, formerly of Spit Road, 5 Mosman, New South Wales, Commonwealth of Australia, and now resident of Glenmore House, Glenmore Road, Minehead, Somerset, England, solicitor, have invented certain new and useful Improvements in or Relating 10 to Railway Safe-Running Devices, of which the following is a specification.

This invention is intended to form one of a series devised by the same inventor for the protection of trains and having for object 15 inter alia to eliminate or minimize the risk due to the personal equation—that is, due to human weakness or fallability.

In apparatus according to this invention a train is adapted, on coming into contact 20 with a track contact, to have an indication given thereon in the event of the presence of a train on a section of track ahead owing to the fact that if the section in question is unoccupied current will flow through a circuit 25 comprising the track contact, train indicating apparatus and a partial circuit on the track so that the current in question will be of a predetermined normal value, whereas if the section is occupied the train occupying 30 it will so affect the track portion of the circuit that the current flowing through the train indicating apparatus will be of such a value as to cause a danger indication to be brought about on the train.

35 Further, according to this invention, means are provided whereby, when a train approaches a section of track containing points or other apparatus relating to the railway track, if a section (hereinafter called a point section) is unoccupied by any obstacle such as another train and all the track and train apparatus is in proper working order, the train is enabled automatically and electrically to unlock the points and 45 subsequently to lock them when they are in the correct position.

The apparatus is also such that an intimation or warning (either visual or audible or both) will be given on the train as to 50 whether it is safe or not safe for the train to run on the point section and subsequently, if the point section is not safe to run on, means are automatically operated whereby

the train will be stopped by the application of the brakes thereon with or without the 55 shutting off of steam or other source of motive power for driving the train.

The invention also comprises, in addition to apparatus adapted to be operated from a moving train to unlock and lock points, 60 means adapted to enable said apparatus to be operated from a track station, said means being adapted when operated to prevent said apparatus from being operated from a moving train.

65 In devising train protecting apparatus of this kind in order that perfect safety may be ensured it is necessary to guard against certain sources of failure in such apparatus including the risk due to the personal equa- 70

75 By providing means for guarding against the various sources of failure, what may be termed "factors of safety" are introduced into the apparatus.

The "factors of safety" are intended to provide against all or any of the following acts or events:—

1. The errors or omissions of a signalman, engine-driver, or the like. 80
2. Breakage of necessary electrical conductors.

3. Failure of a generator to give the current required, when required, for duly effecting any necessary operations for the testing or operating purposes hereinafter mentioned. 85

4. Cases of short-circuit or excess current through part of the means for the said testing or operating purposes. 90

95 "Factors of safety" are introduced firstly, with regard to the omissions of signalmen or engine-drivers, by making the apparatus for stopping the train entirely automatic and dependent only on the state of the track, and secondly with regard to breakage of conductors or failure of a generator, by making the automatic train stopping apparatus to work on what may be termed a "negative system". By a "negative system" is here 100 meant a system in which the train stopping mechanism is normally held inoperative by electrical means against the action of some non-electrical force, such as gravity, a spring or fluid pressure. If then, from any 105 cause, the electrical circuit containing the

electrical controlling means is interrupted or broken, the train will be automatically stopped. Other "factors of safety" are introduced by causing the electric circuit first mentioned to be broken except when certain conditions hold. In the apparatus according to the present invention the circuit is broken unless current of a certain "predetermined normal value" flows through track and train circuits and this only occurs in certain conditions of the track and apparatus connected thereto—that is, when the point section is clear of obstructions and when the electric circuits both on the train and track are complete and in order, a condition which is satisfied only if the generator is working satisfactorily, all electric conductors are unbroken, the points are home, and the unlocking and locking operation has been properly performed by the track apparatus.

The various features of the invention are hereinafter set out in the claims appended hereto and the invention is illustrated by the accompanying drawings which represent diagrammatically and by way of example, apparatus according thereto.

Fig. 1 is a diagrammatic view of a generator and its connexions to a contact shoe and other means on a locomotive. Fig. 2 is a diagram showing point unlocking and locking apparatus and appurtenant apparatus together with connexions to the rails and track contacts of the track.

Attached to, and insulated from, any desirable part of the locomotive is a contact shoe A (Fig. 1) adapted to be moved to different extents by contact with contacts placed on or about a railway track. The shoe A is connected through its casing, wire 12, coil of solenoid B, and wire 11, with a generator or source of electrical energy (hereinafter called a generator) 10, and thence by wire 22, contacts 9 (when bridged by contact plate on lever 33), and wire 23 with any convenient part of the engine frame.

Attached to, and insulated from, the contact shoe A is a resilient bridging contact member 1 comprising fingers arranged to bridge, when the shoe is in its lowest position, the contact plates 2, 3, and 4, and so complete two circuits—namely, (a) from the generator 10, through a branch from wire 11 to contact plate 2, bridging member 1, contact 3, wire 15, wire 16, coil of solenoid C, and wire 21, frame of locomotive, wire 23, contacts 9, and wire 22, and thereby to energize the solenoid C and hold closed a valve 34 controlling means either for shutting off steam from the locomotive or for applying brakes on the train, or both; and (b) from the generator 10, through a branch from wire 11 to contact plate 2, bridging member 1, contact 4, wire 14, wire 17, coil

of solenoid D, wire 18, coils of magnet 19, wire 20, frame of locomotive, wire 23, contacts 9, and wire 22, and thereby to energize the solenoid D and keep valve 31 closed, against the action of fluid pressure which is always tending to open it, to prevent the whistle 32 from being blown and also to energize the magnet 19, so as to attract its armature and maintain the visual signal 29 in the clear or off position.

The shoe A, when passing over a contact such as 40, is raised, causing the bridging member 1 to pass off the contact 4, thereby breaking the connexion between the contacts 2 and 4, and, as far as the bridging member is concerned, opening the circuit relating to the solenoid D and magnet 19, so that, unless the circuit of the solenoid D and magnet 19, is otherwise maintained, the whistle 32 is blown and the miniature signal 29 is raised into the caution position.

When the shoe A is still further raised by a contact such as 41, the bridging member is moved away from contact with the contacts 2 and 3, thereby breaking the circuit of the solenoid C, and, unless other means maintain the circuit through the same, allowing the plunger of the solenoid C to be forced out by whatever pressure may be acting on the valve 34, and to move with it the lever 33 (used for replacing the same) which then breaks, at the contacts 9, the connexion between the generator 10 and the frame of the locomotive. It is intended that the opening of the valve 34, controlled and normally held closed by the plunger of the solenoid C, should allow or cause the admission of fluid pressure, such as of steam or of air, to a suitable cylinder or cylinders having a piston or pistons or the like working therein and arranged in a known manner to close or throttle the steam supply to the locomotive or operate means controlling the application of brakes, or both.

Simultaneously with the raising of the contact shoe A by contact with the track contact 40 or 41, a circuit from the generator 10, through the solenoid B, the shoe A, and the devices connected between the track contacts and the rail or earth is completed or not according to the condition of such devices and the connexions thereto. If that condition is normal the resultant current flowing through B attracts its plunger 28 and the pivoted arm 8 attached to its lower end until the brass or other suitable metallic extension of the plunger, which slides within the coil of B, comes into contact with the hinged stop 37. The resistance which the said stop offers to the further movement of the plunger 28 is controllable by means of an adjustable spring 35, which is so adjusted that, when the current flowing through the solenoid B exceeds the normal, it moves the stop 37 away from a contact

27. The attraction of the plunger, due to current of, but not exceeding, such normal value flowing through the solenoid B, results in the bringing of the pivoted arm 8 into contact with the contacts 6 and 7, insulated from the frame 38 of B, and in the completion of circuits by wires 11 and 13, insulated contact 27, stop 37, frame 38, arm 8, through the contacts 6 and 7 and the coils 10 of the solenoids C, D and magnet 19, which are normally energized by the currents that are broken by the lifting of the shoe A by the contact 41. At the same time the arm 8 makes contact with the contact 5, also 15 insulated from the frame of B, and completes a circuit from the generator 10, through wire 11, wire 13, contact 27, stop 37, arm 8, contact 5, wire 24, bell 25, wire 26, and the frame of the locomotive, so that the ringing of 20 the bell 25 gives an audible signal indicating that normal conditions exist in the circuits exterior to the moving locomotive, which are connected to the track contact with which it interacts. If such is not the 25 case, when the shoe A passes over a contact such as 40, if failure is due to the fact that sufficient current does not flow through the solenoid B, owing to breakage of conductors or the like, the arm 8 is not raised into contact with the contacts 5, 6, and 7, and the 30 bell does not give a clear signal, whilst owing to failure of current in the coils of D and 19 due to the non-completion of the substitutional circuit the whistle 32 is blown and the miniature signal 29, under the influence 35 of the spring 36, goes to caution or danger. If, on the other hand, the resistance of the circuits external to the shoe A is lowered, as by short-circuiting in or of connected devices or by excessive leakage, and the current rises above the normal value, then the increased attraction of the plunger 28 overcomes the resistance of the spring 35 controlling the stop 37, thereby breaking at the insulated contact 27, the connexion between 40 the generator 10 and the frame 38 of B, and the whistle 32 and signal 29 are operated as hereinbefore described. Similarly, when the shoe A passes over a contact such as 45 41, whether there is failure of normal current or the current is above the normal, in addition to the blowing of the whistle and the movement of the signal to the danger position the solenoid C is de-energized so that the brakes are applied, with or without the shutting off of the motive power of the train, and the generator 10 is, as above described, disconnected at the contacts 9 from the frame of the locomotive and will remain 50 disconnected therefrom until again connected by means of the handle 33. The said handle 33 and the solenoid C are preferably enclosed in a suitable cover or box and locked therein. Hence it will be seen that 55 on the passage of a train, adapted as de-

scribed to interact with contacts on or about the railway track there will be given either a visual and audible clear signal or a visual and audible warning on the train, or the train will be both warned and stopped according to the condition of the circuits of which the track contacts form part. From the foregoing description of the figure it will be seen that the operation of the apparatus is automatic with the exception of 70 the replacing of the plungers of the solenoids C and D, by means of the levers 33 and 30, into such positions that when current flows through the coils the plungers and the valves connected thereto are held against 75 the opposing forces acting on them.

It should be understood that, in order that the connexion at the locomotive contacts 2, 3, and 4 may not be broken until the current through the track circuits shall have 80 reached its full stationary value, the ends of the track contacts such as 40 and 41 are inclined at such an angle or are of such a length as to give the necessary time interval between the first contact of the shoe A 85 with each of such track contacts and the breaking of either of the locomotive contacts at 3 or 4, for the current through the track circuits in question to have reached its 90 constant value.

Fig. 2 shows an arrangement for unlocking and locking points by electrical means, and the disposition of electrical connexions relating to a section of track including the points, the condition of which controls or 100 permits the unlocking or locking of such points, either from an advancing train or from a place adjacent to them. The electrical means shown are adapted to co-operate with the apparatus shown in Fig. 1 so as to 105 indicate the condition of such point section and, if required, to warn the train and if necessary to stop it from proceeding along the section in the case of danger.

On the branch and in both directions on 110 the main line distant from the points, are arranged the contacts 39, 40, and 41 for interacting with the contact shoe A (Fig. 1) carried on the locomotive or train. The contacts 39 and 40 produce equal extents of 115 movement, while the contact 41 causes a greater extent of movement or travel, of the shoe A. The contacts 39, 40, and 41 are in each case inside the track section, the said contacts 39 and 40 being sufficiently distant 120 from the contact 41 for a driver on passing over either contact 39 or 40, to stop his train where required before passing over the said contact 41, and the said contact 41 being sufficiently distant from the points to enable 125 a train, when required, to be automatically stopped thereby after passing over the same before reaching the points.

The point lock M may be of any known construction, but is preferably of the type 130

in which a slot in the locking bolt, when in the unlocking position, comes into alignment with the body of the stretcher bar so as to permit the stretcher bar to be freely moved, 5 and in which, when the points have been thrown fully over into either position, a similar slot in the stretcher bar comes opposite the bolt and permits the bolt to be moved into the locking position. The locking bolt 10 is directly attached to a movable plunger common to the solenoids K and J, for unlocking and locking respectively. By means of a catch on the cranked extension 62 of the armature of the magnet L and a projecting 15 lug on the plunger in the space between J and K, the plunger can in turn be locked in position after completing its stroke. The arrangement and connexions of the windings of the magnet L and solenoids K and J 20 are such that, on a current being put into L and either K or J which at the time is in series with it, the whole of the coil L and only part of K or J receives current, but, on the attraction of the armature of L to an 25 extent sufficient to release the lock 62, the circuits are rearranged so that the larger portion of the coil L is cut out and the whole of the coil of either K or J is put into the 30 circuit. The object of this arrangement is to obtain a rapid action of both armature and plunger with minimum waste of energy and at the same time the resistance of the coils affected is maintained at an approximately uniform value.

35 When a train is running towards the facing points and its contact shoe A passes over a track contact 39, a current flows from the generator on the train, through the shoe A and contact 39, by wire 42, to magnet G (the 40 attraction of the armature of which breaks at the contact 107, the connexion between the wires 69 and 57 and so disconnects the solenoid J), wire 46 to magnet N, wire 47 to rail 76, wire 96, contacts 103 until magnet N 45 is energized, and subsequently wire 60, contacts 106 (bridged by the attracted armature of N, the resiliency of the contact fingers at 103 permitting of the establishment of contact at 106 before that of 103 is finally 50 broken), and wire 63, and thence by wire 97, rail 78, wire 48, whole of coil L, wire 53, contacts 61, wire 54, branch wire 55, portion of coil K, wire 56, contact 108, armature of F, wire 69, to contacts 50, wire 49 to rail 55 80, wire 81, rail 118, wire 119, and rail 82 to the wheels and frame of the locomotive or train. The energizing of the magnet L attracts its armature and releases the catch 62, on the cranked extension thereof, from 60 engagement with the common plunger of the solenoids J and K and breaks, at the contact 61, the connexion between the wires 53 and 54, but simultaneously makes, at the contacts 59, a path from part of the winding of 65 L, through wire 52, contacts 59, wire 58,

and the whole of the coil K to wire 56, and thence back to the rail 82 as before described. The energizing of the solenoid K attracts its plunger with the attached locking bolt and, by withdrawing it from engagement with the 70 stretcher bar, unlocks the points. The plunger, when over in the unlocked position, effects contact, by means of an insulated contact plate on a projecting portion thereof, 75 between the wires 114 and 115 at the contacts 110, and completes a circuit, from the rail 76, through the wires 96 and 60, the contacts 106, the wire 114, contacts 110, wire 115, resistance 116 and wire 113 to rail 82, so that the coils L and K are shunted. 80 The effect of this shunt path is to produce a current (which is greater than that necessary to withdraw the locking bolt), through the solenoid B on the train, which is of what I have called "predetermined normal value," 85 and which will restrain a warning operation and produce a line-clear intimation on the train. By current of "predetermined normal value" is meant a current which is sufficient on energizing the solenoid B to operate its plunger so as to complete the aforesaid substitutional circuits on the train but it is insufficient to break the train circuits by breaking the contact between the contact 27 and the stop 37. If, however, the plunger 95 is not moved over into the unlocking position the above described shunt circuit will not be completed at the contacts 110 and a warning operation will therefore be produced on the train, owing to failure of current of 100 predetermined normal value to flow through the solenoid B on the train.

The train proceeding, the contact shoe A makes contact with the track contact 40 and current then flows from the generator on 105 the train, through wire 43, resistance 117, magnet F, wire 46, magnet N, wire 47, to rail 76, and as before, through wires 96 and 60, contacts 106, wires 63 and 97, rail 78, wire 48, whole of coil L, wire 53, contacts 110 61, wire 54, portion of coil J, wire 57 to contact 107, armature of G, wire 69, contacts 50, wire 49, to rail 80, wire 81, rail 118, wire 119, and rail 82 to the wheels and frame of the locomotive or train. The attraction of the armature by L releases the 115 catch 62, cuts out portion of the coil of L at the contacts 61, and, by the bridging of the contacts 59, connects through wires 52 and 48, the remaining part of the coil L with the whole of the coil J. The energizing of the coil J attracts the common plunger with the attached locking bolt, which, 120 engaging with the slot or orifice in the stretcher bar, locks the points in position. When the points are locked the insulated projecting contact plate on the plunger completes at the contacts 109, a path, from the rail 76, by wires 96 and 60, contacts 106, wire 114, contacts 109, wire 111, resistance 125 130

112, and wire 113 to rail 82, so as to parallel the coils J and L. The value of the resistance 112 is such that the current which flows from the train through the resistance 5 117 and the coils L and J shunted by the resistance 112 is equal approximately to the current which flows from the train through the coils K and L when shunted by the resistance 116 the value of which may differ 10 considerably from that of 112, but is compensated for by the addition of the resistance 117 in the locking circuits in order that the current through B (Fig. 1) may, when 15 the locking operation has been duly performed, be of "predetermined normal value", so that the production of a warning operation on the train is restrained and a line-clear intimation given. If, however, 20 the plunger is not moved over into the locking position, the above described shunt circuit will not be completed at the contacts 109, and a warning operation will therefore be produced on the train, owing to 25 failure of current of predetermined normal value to flow through the solenoid B on the train.

When current ceases to flow through L its armature is drawn away by the influence 30 of gravity or a spring or both, and the catch 62, forming part of the cranked extension of the armature engages with the projecting lug on the plunger and so locks the plunger in position if it has completed its stroke. When the train passes over the contact 41 its contact shoe makes contact therewith, and current flows, as before, from the generator on the train, through portion of the wire 44, wire 45, contacts 64, wire 65, and either 66 or 67 and 68 (according to 40 the position of the points) to wire 43, and through the coils F, N, J and L as before described for track contacts 40. The arrangement and disposition of the contacts at the points and the insulated fingers attached 45 to the moving blades of the same, prevent the connexion between the wires 65 and 68 from being made, if the points themselves have spread sufficiently to be dangerous, or are not right home.

50 When, after the train has passed over the points, the contact shoe A again makes contact with the track contacts the operations are repeated in reverse order—that is, the checking or testing is the first, and the unlocking of the points the last, operation. If 55 the train approaches the points from the opposite direction to that assumed, either on the branch or the main line, the description hereinbefore given holds good with the exception that the return path to the train may vary; in the case of a train on the branch the return would only include a portion of the rail 118, wire 81, and the bonded section of rails 80 and wire 49, but in the 60 case of a train on the main line the return

would be through the wire 49 and the bonded rails 80 only. It should be explained that the functions of the magnet N when energized are (1) to cut out, at contacts 104, 105 and 102, the extraneous parallel circuits through rail 78, wire 99, contacts 104, wire 98, rail 77, wire 100, contacts 105, wire 101, rail 120 and resistance 86, and through contacts 102, wire 75, rail 74, wire 72, resistance 72^a, contacts 90, 89, wire 71, battery 70, 75 wire 83, magnet E, and wire 87, which are not required for performing the operations just described, the objects being to prevent a train, when interacting with a track contact 41, from automatically stopping itself 80 owing to the completion, by means of those parallel circuits, of a circuit which would be of practically no resistance because of its own presence on the rails 120, 80, 77, 118, or 74, 82, as the case may be, and to confine 85 the leakage to that between the comparatively short bonded lengths of rail 76 and 76^a and 78, and the rail 82 and its connexions and (2) to make, through wires 96 and 60 and the contacts 106, a path through 90 the shunt resistances 112 or 116 to the rail. The completion of the operations just described, from and by an advancing train without warning or stopping the same, being dependent on the maintaining of current strength of "predetermined normal value" through the magnet B (Fig. 1) when 95 the shoe is passing over the contacts 39, 40, and 41 it follows that, unless the plunger with the attached locking bolt is home in 100 one position or the other, making at the contacts 109 or 110 the shunt to the operating coils, and the points themselves are in order, current of "predetermined normal value" 105 will not flow through B, and the advancing train will be warned or warned and stopped. Further, if vehicles are standing on the bonded point section of track they shunt the coils L, K, and J and an advancing train will be warned of their presence 110 when passing over contacts 39 and 40 and have steam shut off and brakes applied, on contacting with the contact 41, owing to the fact that the current through B exceeds the 115 "predetermined normal value" on account of the shunting of the coils L, K and J by the wheels and axles of the train in the area mentioned. Conversely, failure of any part of the circuit including the generator on the train and the contact shoe, and the parts 120 external thereto will result in the similar warning and stopping of the train when passing over the contacts 39, 40, and 41 respectively.

For the purpose of enabling the points 125 to be unlocked or locked apart from the train there may be provided, in a signal box or place adjacent thereto, a battery or other generator 70 connected to a switch (comprising the extension 88 for bridging 130

the segments 89 and 90 and the contacts 91 and 92) shown attached to the catch handle of part of a lever H (which may be either the lever working the points or merely 5 a device used for switching purposes). On grasping and closing the catch handle, the extension 88 effects contact with and bridges the segments 89 and 90, which, together with the contacts 91 and 92, are insulated 10 from each other and from the lever, thereby completing a circuit through wire 71, resistance 72^a, wire 72, rail 74, wire 75, armature of N and contact 102, wire 47, rail 76, wire 96, contacts 103, wire 97, rail 78, wire 15 99, contacts 104, wire 98, rail 77, wire 100, contacts 105, wire 101, rail 120, resistance 86, rail 80, wire 81, rail 118, wire 119, rail 82, wire 87, magnet E, and wire 83 to part of the battery 70. When current flows 20 through E of a value corresponding to the state of the tracks so connected but unoccupied by vehicles, the armature 94 of E is attracted sufficiently to effect contact with the pivoted stop 51, which is weighted or 25 otherwise controlled to limit the travel of the armature when currents of the value mentioned traverse the coil of E. The attraction of the armature 94 breaks, at the contacts 50, connexion between the wires 30 49 and 69, and so disconnects the coils J, K, and L from the rail 80, thereby preventing any advancing train from operating the point lock from the contacts 39, 40, and 41 while the points are in the course of being 35 moved from the signal box. The attraction of the armature 94 further makes a connexion between the whole of the battery 70 and the coils L and K, or J, by means of the wire 73, the armature 94, stop 51, contact 95, and the branch to wire 69. If current, within the limits of value to which E has been adjusted, does not flow, owing to 40 the shunting of the resistance 86 by a vehicle on the track or to failure of the circuits, the armature 94 is either not lifted (owing to failure of the battery or derangement of the circuit) or is attracted with sufficient force to lift the stop 51 from its contact 95 (owing to excess current resulting 45 from the shunting of some portion of the circuit containing the magnet E by vehicles standing or moving on the bonded track section, or to the production of a short or cross circuit therein). It is intended that a disc be attached to the armature 94, or an extension thereof, to indicate the three relative positions of the same to show the condition of the track when testing, that is (1) when the armature 94 is at rest owing to no (or insufficient) current passing through the magnet E to attract it, 50 (2) when the armature 94 is attracted by the normal strength of current through E, corresponding to the tracks being unoccupied, and (3) when the armature 94 is at-

tracted by excess current through E, resulting from the production of a short or cross between the wires 72 and 87, or from the presence of vehicles on the bonded track section, and the shunting of the resistance 70 75 86. It follows that, if the bonded track section is occupied, the circuits enabling the points to be operated from the box are not made and the same cannot be interfered with after a train, advancing from any direction, has entered the track section until it has, on running out of such section, cleared them and left the points free to be again set for either road from the signal box.

With the tracks unoccupied, and normal current flowing through the coil E, the armature 94 is attracted, so that it makes contact with the stop 51 and provides a path from the generator 70, through wire 73, armature 94, stop 51, contact 95, to wire 69, 85 which is completed to the generator through either (a) the wire 71, contacts 89 and 91 bridged by 88, wire 84, wire 42, magnet G (which attracts its armature and breaks the connexion to coil J), wires 46 and 47 (bridged 90 at the contacts 93 by the armature 94), rail 76, wire 96, contacts 103, wire 97, rail 78, wire 48, coils L and K, wire 56, contact 108, and armature of the magnet F which is joined to the wire 69, thus unlocking the 95 points; or (b) the wire 71, contacts 89 and 92 bridged by 88, wire 85, wire 43, resistance 117, magnet F, wires 46 and 47 (bridged at the contacts 93 by the armature 94), rail 76, wire 96, contacts 103, wire 97, 100 rail 78, wire 48, coils L and J, wire 57, contact 107, and armature of the magnet G which is connected to the wire 69, thus locking the points—that is to say, the closing of the catch handle on H to the fullest extent 105 unlocks the points if the tracks are clear, and, after throwing the lever H (if the point operating lever), the momentary restraining of the catch handle after the operation of throwing the points has been completed enables the locking of the points to be effected through the contacts 89 and 92 which are then bridged by the extension 88.

At the instant of switching, a current flows momentarily from part of the generator 70 through a circuit containing the magnet E, and the coils L and the coils J and K in parallel, normally shunting the resistance 86, but, as the armature 94 moves away from the contacts 50, the shunting 115 circuit containing L and J and K is broken and the current through E is then determined by the resistance of the circuit including 86 and 72^a, which (apart from the variations due to leakage) determines its 120 value when the resistance 86 is not shunted by a vehicle. If the circuit is complete, the value of the current passing through the magnet E is dependent on whether the track 125 is occupied or not. The bridging of the 130

5 contacts 93 by the attraction of the armature 94 shunts the magnet N, so that, when the operations of unlocking and locking are carried on apart from the train, the resistances 112 and 116 cannot shunt the coils L, K, and J, or the resistance 86.

The movement of the points or switches themselves may be effected in any suitable manner.

10 When the section of track does not contain points the apparatus hereinbefore specifically described may obviously be much simplified by the omissions of such circuits as are only necessary for operating the point unlocking or locking apparatus from a train or from a track station. Also when it is only desired to operate the unlocking or locking apparatus from a track station, the track contacts and connexions thereto may 15 conveniently be omitted.

15 The means on the locomotive, or brakevan or the like, for applying the brakes on the train, or shutting off the motive power of the train, may comprise one or more cylinders with a suitable piston or pistons or the like. This piston or one of these pistons is connected with the brake lever for applying the brakes on the train, and, if it is desired also to shut off the motive power of the 20 train, the piston or the other of the pistons is suitably connected with the lever for shutting off the power of the train.

25 By the term "train" I herein include (except where otherwise inconsistent therewith) the following railway vehicles—locomotive, carriage, car, truck, brakevan, or the like rolling stock: and the term "train" also includes a locomotive coupled to any suitable number of above railway vehicles.

30 40 Various modifications may be made without departing from the scope of the invention.

What I claim is:—

1. Train protecting apparatus comprising indicating apparatus on a train constantly tending to operate, restraining means adapted normally to restrain the operation of said indicating apparatus, a normally de-energized electromagnetic device carried by said train and adapted when energized by current of a predetermined normal value also to cause restraint of the operation of said indicating apparatus, a normally open electric circuit arranged partly on the train and partly on the track and adapted to include said electromagnetic device and a generator of electricity, the track portion of said circuit being adapted to have its resistance, which is normally of a value to allow the flow through the said electromagnetic device of current of said predetermined normal value, varied by a train in a particular section of track, and means including a track contact and adapted to close said circuit and then to affect said restraining means so as to remove the restraint thereon.
2. Train protecting apparatus comprising indicating apparatus on a train constantly tending to operate, restraining means adapted normally to restrain the operation of said indicating apparatus, a normally de-energized electromagnetic device carried by said train and adapted when energized by current of a predetermined normal value also to cause restraint of the operation of said indicating apparatus, a normally open electric circuit arranged partly on the train and partly on the track and adapted to include said electromagnetic device and a generator of electricity, the track portion of said circuit being adapted to have its resistance, which is normally of a value to allow the flow through the said electromagnetic device of current of said predetermined normal value, varied by a train in a particular section of track, and means including a track contact and adapted to close said circuit and then to affect said restraining means so as to remove the restraint thereon.
3. Train protecting apparatus comprising indicating apparatus on a train constantly tending to operate, electromagnetic means adapted when energized to prevent the operation of said indicating apparatus, a generator of electricity on said train, a normally closed electric circuit including said generator and said electromagnetic means, a normally open second circuit on said train adapted to include said generator and said electromagnetic means, a normally de-energized electromagnetic device on said train adapted when energized by current of a predetermined normal value to complete said second circuit, a normally open third circuit arranged partly on the train and partly on the track and adapted to include said electromagnetic device and a generator of electricity, the track portion of said circuit being adapted to have its resistance, which is normally of a value to allow the flow through the circuit of current of said predetermined normal value, varied by a train in a particular section of track, and means including a track contact and adapted to close said third circuit and then to break the first mentioned circuit.
4. Train protecting apparatus comprising indicating apparatus on a train constantly tending to operate, restraining means adapted normally to restrain the operation of said indicating apparatus, a normally de-energized electromagnetic device carried by said train and adapted when energized by current of a predetermined normal value, varied by a train in a particular section of track, and means including a track contact and adapted to close said circuit and then to affect said restraining means so as to remove the restraint thereon.

rent of a predetermined normal value also to cause restraint of the operation of said indicating apparatus, a normally open electric circuit arranged partly on the train and partly on the track and adapted to include said electromagnetic device, a generator of electricity, the track rails on opposite sides of a section of track, and a resistance device which normally allows the flow through the

10 said electromagnetic device of current of said predetermined normal value, but which is adapted to be short-circuited by a train standing on the said track rails of the said section, and means including a track contact 15 and adapted to close said circuit and then to affect said restraining means so as to remove the restraint thereof on the operation of said indicating apparatus.

5. Train protecting apparatus comprising 20 indicating apparatus on a train constantly tending to operate, electromagnetic means adapted when energized to prevent the operation of said indicating apparatus, a generator of electricity on said train, a normally closed electric circuit including said generator and said electromagnetic means, a normally open second circuit on said train adapted to include said generator and said electromagnetic means, a normally de-energized electromagnetic device on said train 25 adapted when energized by current of a predetermined normal value to complete said second circuit, a normally open third circuit arranged partly on the train and partly on 30 the track and adapted to include said electromagnetic device, a generator of electricity, the track rails on opposite sides of a section of track, and a resistance device which normally allows the flow through the said electromagnetic device of current of said predetermined normal value, but which is adapted 35 to be short-circuited by a train standing on the said track rails of the said section, and means including a track contact and adapted 40 to close said third circuit and then to break the first mentioned circuit.

6. Train protecting apparatus comprising 45 track apparatus relating to the making of a clear road for a train along a railway track, a locking device adapted to lock said track apparatus, electromagnetic means adapted when energized to cause the locking operation of said locking device, a track contact on said track, a generator of electricity, a contacting device on said train, a normally open electric circuit arranged 50 partly on said train and partly on said track and adapted to be completed through said generator and through said electromagnetic means on contact of said contacting device with said track contact, said electric circuit being adapted to have the flow of current through the train portion thereof on contact of said contacting device with said 55 track contact normally of a predetermined

value, but affected by a train in a particular section of track, indicating apparatus on said train constantly tending to operate but normally under a restraint adapted to be removed on contact of said contacting device 60 with said track contact, and electromagnetic means on said train included in said circuit and adapted when energized by the flow therethrough of current of said predetermined normal value to restrain the operation 65 of said indicating apparatus.

7. Train protecting apparatus comprising track apparatus relating to the making of a clear road for a train along a railway track, a locking device adapted to lock said track 70 apparatus, electro-magnetic means adapted when energized to cause the locking operation of said locking device, a track contact on said track, a generator of electricity, a contacting device on said train, an electric circuit arranged partly on said train and partly on said track and adapted to be completed through said generator and through said electro-magnetic means on contact of 75 said contacting device with said track contact, indicating apparatus on said train, and electro-magnetic means on said train adapted to cause the operation of said indicating apparatus, according to the flow of current therethrough, said locking device being 80 adapted to control the said flow of current.

8. Train protecting apparatus comprising track apparatus relating to the making of a clear road for a train along a railway track, a locking device adapted to lock said track apparatus, electro-magnetic means adapted when energized to cause the locking operation of said locking device, a track contact on said track, a generator of electricity, a contacting device on said train, an electric circuit arranged partly on said train and partly on said track and adapted to be completed through said generator and through said electro-magnetic means on contact of 85 said contacting device with said track contact, indicating apparatus on said train, and electro-magnetic means on said train adapted to cause the operation of said indicating apparatus according to the flow of current therethrough, said track apparatus 90 and said locking device being both adapted to control the said flow of current.

9. Train protecting apparatus comprising track apparatus relating to the making of a clear road for a train along a railway track, an unlocking device adapted to unlock said track apparatus, electro-magnetic means adapted when energized to cause the unlocking operation of said unlocking device, a track contact on said track, a generator of 100 electricity, a contacting device on said train, an electric circuit arranged partly on said train and partly on said track—and adapted to be completed through said generator and through said electro-magnetic means on 105 contact of said contacting device with said track contact, indicating apparatus on said train, and electro-magnetic means on said train adapted to cause the operation of said indicating apparatus according to the flow of current therethrough, said track apparatus 110 and said locking device being both adapted to control the said flow of current.

contact of said contacting device with said track contact, indicating apparatus on said train, and electro-magnetic means on said train adapted to cause the operation of said indicating apparatus according to the flow of current therethrough, said track apparatus being adapted to control the said flow of current.

10. Train protecting apparatus comprising track apparatus relating to the making of a clear road for a train along a railway track, an unlocking device adapted to unlock said track apparatus, electro-magnetic means adapted when energized to cause the unlocking operation of said unlocking device, a track contact on said track, a generator of electricity, a contacting device on said train, an electric circuit arranged partly on said train and partly on said track and adapted to be completed through said generator and through said electro-magnetic means on contact of said contacting device with said track contact, indicating apparatus on said train, and electro-magnetic means on said train adapted to cause the operation of said indicating apparatus according to the flow of current therethrough, said unlocking device being adapted to control the said flow of current.

30 11. Train protecting apparatus comprising track apparatus relating to the making of a clear road for a train along a railway track, an unlocking device adapted to unlock said track apparatus, electro-magnetic means adapted when energized to cause the unlocking operation of said unlocking device, a track contact on said track, a generator of electricity, a contacting device on said train, an electric circuit arranged partly on said train and partly on said track and adapted to be completed through said generator and through said electro-magnetic means on contact of said contacting means with said track contact, indicating apparatus on said train, and electro-magnetic means on said train adapted to cause the operation of said indicating apparatus according to the flow of current therethrough, said track apparatus and said unlocking device being both adapted to control the said flow of current.

55 12. Train protecting apparatus comprising track apparatus relating to the making of a clear road for a train along a railway track, a locking and unlocking device adapted to lock and unlock said track apparatus, electro-magnetic means adapted when energized to cause the locking operation of said device, electro-magnetic means adapted when energized to cause the unlocking operation of said device, two track contacts on said track, a generator of electricity, a contacting device on said train, an electric circuit arranged partly on said train and partly on said track and adapted to be completed

60 65

through said generator and through the first mentioned electro-magnetic means on contact of said contacting device with one of said track contacts, an electric circuit arranged partly on said train and partly on said track 70 and adapted to be completed through said generator and through the secondly mentioned electro-magnetic means on contact of said contacting device with the other of said track contacts, indicating apparatus on said train, and electro-magnetic means on said train adapted to cause the operation of said indicating apparatus according to the flow of current therethrough, said track apparatus 75 being adapted to control the said flow of 80 current.

13. Train protecting apparatus comprising track apparatus relating to the making of a clear road for a train along a railway track, a locking and unlocking device adapted to lock and unlock said track apparatus, electro-magnetic means adapted when energized to cause the locking operation of said device, electro-magnetic means adapted when energized to cause the unlocking operation of said device, two track contacts on said track, a generator of electricity, a contacting device on said train, an electric circuit arranged partly on said train and partly on said track and adapted to be completed through said generator and through the first mentioned electro-magnetic means on contact of said contacting device with one of said track contacts, an electric circuit arranged partly on said train and partly on said track and adapted to be completed through said generator and through the secondly mentioned electro-magnetic means on contact of said contacting device with the other of said track contacts, indicating apparatus on said train, and electro-magnetic means on said train adapted to cause the operation of said indicating apparatus according to the flow of current therethrough, said locking and unlocking device being adapted to control the said flow of current. 85 90 95 100 105

14. Train protecting apparatus comprising track apparatus relating to the making of a clear road for a train along a railway track, a locking and unlocking device adapted to lock and unlock said track apparatus, electro-magnetic means adapted when energized to cause the locking operation of said device, electro-magnetic means adapted when energized to cause the unlocking operation of said device, two track contacts on said track, a generator of electricity, a contacting device on said train, an electric circuit arranged partly on said train and partly on said track and adapted to be completed through said generator and through the first mentioned electro-magnetic means on contact of said contacting device with one of said track contacts, an electric circuit arranged partly on said train and partly on 115 120 125 130 135

said track and adapted to be completed through said generator and through the secondly mentioned electro-magnetic means on contact of said contacting device with the 5 other of said track contacts, indicating apparatus on said train, and electro-magnetic means on said train adapted to cause the operation of said indicating apparatus according to the flow of current therethrough, said 10 track apparatus and said locking and unlocking device being both adapted to control the said flow of current.

15. Train protecting apparatus comprising track apparatus relating to the making of a clear road for a train along a railway track, a locking device adapted to lock said track apparatus, electromagnetic means adapted when energized to cause the locking operation of said locking device, a track 20 contact on said track, a generator of electricity, a contacting device on said train, a normally open electric circuit arranged partly on said train and partly on said track and adapted to be completed through said 25 generator and through said electromagnetic means on contact of said contacting device with said track contact, said electric circuit being adapted to have the flow of current through the train portion thereof on contact of said 30 contacting device with said track contact normally of a predetermined normal value, but affected by a train in a particular section of track, indicating apparatus on said train constantly tending to operate but normally 35 under a restraint adapted to be removed on contact of said contacting device with said track contact, and electromagnetic means on said train included in said circuit and adapted when energized by the flow therethrough of current of said predetermined 40 normal value to restrain the operation of said indicating apparatus, said track apparatus being also adapted to control the said flow of current.

45. 16. Train protecting apparatus comprising track apparatus relating to the making of a clear road for a train along a railway track, a locking device adapted to lock said track apparatus, electromagnetic means adapted when energized to cause the locking 50 operation of said locking device, a track contact on said track, a generator of electricity, a contacting device on said train, an electric circuit arranged partly on said 55 train and partly on said track and adapted to be completed through said generator and through said electromagnetic means on contact of said contacting device with said track contact, said electric circuit being 60 adapted to have the flow of current through the train portion thereof on contact of said contacting device with said track contact normally of a predetermined normal value, but affected by a train in a particular section 65 of track, indicating apparatus on said train

constantly tending to operate but normally under a restraint adapted to be removed on contact of said contacting device with said track contact, and electromagnetic means on said train included in said circuit and 70 adapted when energized by the flow therethrough of current of said predetermined normal value to restrain the operation of said indicating apparatus, said locking device being also adapted to control the said 75 flow of current.

17. Train protecting apparatus comprising track apparatus relating to the making of a clear road for a train along a railway track, a locking device adapted to lock 80 said track apparatus, electromagnetic means adapted when energized to cause the locking operation of said locking device, a track contact on said track, a generator of electricity, a contacting device on said train, an electric circuit arranged partly on said train and partly on said track and adapted to be completed through said generator and through said electromagnetic means on contact of said contacting device with said track contact, said electric circuit being adapted to have the flow of current through the train portion thereof on contact of said contacting device with said track contact normally of a predetermined normal value, but affected by a train in a particular section of track, indicating apparatus on said train constantly tending to operate but normally 90 under a restraint adapted to be removed on contact of said contacting device with said track contact, and electromagnetic means on said train included in said circuit and adapted when energized by the flow therethrough of current of said predetermined normal value to restrain the operation of said indicating apparatus, said track apparatus and said locking device being also adapted to control the said flow of current.

18. Train protecting apparatus comprising track apparatus relating to the making of a clear road for a train along a railway track, an unlocking device adapted to unlock said track apparatus, electromagnetic means adapted when energized to cause the 100 unlocking operation of said unlocking device, a track contact on said track, a generator of electricity, a contacting device on said train, an electric circuit arranged partly on said train and partly on said track and 105 adapted to be completed through said generator and through said electromagnetic means on contact of said contacting device with said track contact, said electric circuit being adapted to have the flow of current through the train portion thereof on contact of said contacting device with said track contact normally of a predetermined normal value, but affected by a train in a particular section of track, indicating apparatus on said train

paratus on said train constantly tending to operate but normally under a restraint adapted to be removed on contact of said contacting device with said track contact, 5 and electromagnetic means on said train included in said circuit and adapted when energized by the flow therethrough of current of said predetermined normal value to restrain the operation of said indicating apparatus, said track apparatus being also adapted to control the said flow of current.

19. Train protecting apparatus comprising track apparatus relating to the making of a clear road for a train along a railway track, an unlocking device adapted to unlock said track apparatus, electromagnetic means adapted when energized to cause the unlocking operation of said unlocking device, a track contact on said track, a generator of electricity, a contacting device on said train, an electric circuit arranged partly on said train and partly on said track and adapted to be completed through said generator and through said electromagnetic 25 means on contact of said contacting device with said track contact, said electric circuit being adapted to have the flow of current through the train portion thereof on contact of said contacting device with said track contact normally of a predetermined normal value, but affected by a train in a particular section of track, indicating apparatus on said train constantly tending to operate but normally under a restraint 30 adapted to be removed on contact of said contacting device with said track contact, and electromagnetic means on said train included in said circuit and adapted when energized by the flow therethrough of current of said predetermined normal value to restrain the operation of said indicating apparatus, said unlocking device being also adapted to control the said flow of current.

20. Train protecting apparatus comprising track apparatus relating to the making of a clear road for a train along a railway track, an unlocking device adapted to unlock said track apparatus, electromagnetic means adapted when energized to cause the unlocking operation of said unlocking device, a track contact on said track, a generator of electricity, a contacting device on said train, an electric circuit arranged partly on said train and partly on said track and adapted to be completed through said generator and through said electromagnetic means on contact of said contacting device with said track contact, said electric circuit being adapted to have the flow of current through the train portion thereof on contact of said contacting device with said track contact normally of a predetermined normal value, but affected by a train in a particular section of track, indicating apparatus on said train constantly tending to operate but normally under a restraint adapted to be removed on contact of said contacting device with said track contact, and electromagnetic means on said train included in said circuit and adapted when energized by the flow therethrough of current of said predetermined normal value to restrain the operation of said indicating apparatus, said track apparatus being also adapted to control the said flow of current.

operate but normally under a restraint adapted to be removed on contact of said contacting device with said track contact, and electromagnetic means on said train included in said circuit and adapted when energized by the flow therethrough of current of said predetermined normal value to restrain the operation of said indicating apparatus, said track apparatus and said unlocking device being also adapted to control the said flow of current.

21. Train protecting apparatus comprising track apparatus relating to the making of a clear road for a train along a railway track, a locking and unlocking device adapted to lock and unlock said track apparatus, electromagnetic means adapted when energized to cause the locking operation of said device, electromagnetic means adapted when energized to cause the unlocking operation of said device, two track contacts on said track, a generator of electricity, a contacting device on said train, an electric circuit arranged partly on said train and partly on said track and adapted to be completed through said generator and through the first mentioned electromagnetic means on contact of said contacting device with one of said track contacts, an electric circuit arranged partly on said train and partly on said track and adapted to be completed through said generator and through the secondly mentioned electromagnetic means on contact of said contacting device with the other of said track contacts, each of said electric circuits being adapted to have the flow of current through the train portion thereof on contact of said contacting device with the corresponding one of said track contacts normally of a predetermined normal value, but affected by a train in a particular section of track, indicating apparatus on said train, constantly tending to operate but normally under a restraint adapted to be removed on contact of said contacting device with each of said track contacts, and electromagnetic means on said train included in each of said circuits and adapted when energized by the flow therethrough of current of said predetermined normal value to restrain the operation of said indicating apparatus, said track apparatus being also adapted to control the said flow of current.

22. Train protecting apparatus comprising track apparatus relating to the making of a clear road for a train along a railway track, a locking and unlocking device adapted to lock and unlock said track apparatus, electromagnetic means adapted when energized to cause the locking operation of said device, electromagnetic means adapted when energized to cause the unlocking operation of said device, two track contacts on said track, a generator of electricity, a contacting device on said train, an electric circuit ar-

ranged partly on said train and partly on said track and adapted to be completed through said generator and through the first mentioned electromagnetic means on contact of said contacting device with one of said track contacts, an electric circuit arranged partly on said train and partly on said track and adapted to be completed through said generator and through the secondary mentioned electromagnetic means on contact of said contacting device with the other of said track contacts, each of said electric circuits being adapted to have the flow of current through the train portion thereof on contact of said contacting device with the corresponding one of said track contacts normally of a predetermined normal value, but affected by a train in a particular section of track, indicating apparatus on said train constantly tending to operate but normally under a restraint adapted to be removed on contact of said contacting device with each of said track contacts, and electromagnetic means on said train included in each of said circuits and adapted when energized by the flow therethrough of current of said predetermined normal value to restrain the operation of said indicating apparatus, said locking and unlocking device being also adapted to control the said flow of current.

23. Train protecting apparatus comprising track apparatus relating to the making of a clear road for a train along a railway track, a locking and unlocking device adapted to lock and unlock said track apparatus, electromagnetic means adapted when energized to cause the locking operation of said device, electromagnetic means adapted when energized to cause the unlocking operation of said device, two track contacts on said track, a generator of electricity, a contacting device on said train, an electric circuit arranged partly on said train and partly on said track and adapted to be completed through said generator and through the first mentioned electromagnetic means on contact of said contacting device with one of said track contacts, an electric circuit arranged partly on said train and partly on said track and adapted to be completed through said generator and through the secondly-mentioned electromagnetic means on contact of said contacting device with the other of said track contacts, each of said electric circuits being adapted to have the flow of current through the train portion thereof on contact of said contacting device with the corresponding one of said track contacts normally of a predetermined normal value, but affected by a train in a particular section of track, indicating apparatus on said train constantly tending to operate but normally under a restraint adapted to be removed on contact of said contacting device

with each of said track contacts, and electromagnetic means on said train included in each of said circuits and adapted when energized by the flow therethrough of current of said predetermined normal value to restrain the operation of said indicating apparatus, said track apparatus and said locking and unlocking device being also adapted to control the said flow of current.

24. Train protecting apparatus comprising track apparatus relating to the making of a clear road for a train along a railway track, a locking device adapted to lock said track apparatus, electromagnetic means adapted when energized to cause the operation of said locking device, a track contact on said track, a generator of electricity, a contacting device on said train, an electric circuit arranged partly on said train and partly on said track and adapted to be completed through said generator and through said electromagnetic means on contact of said contacting device with said track contact, indicating apparatus on said train, electromagnetic means on said train included in said circuit and adapted to prevent the operation of said indicating apparatus when energized by current of a predetermined normal value, and a resistance adapted to be connected in said circuit by said locking device when in its locking position and of such a value as to cause current of said predetermined normal value to flow through said electromagnetic means and thereby to prevent the operation of said indicating apparatus.

25. Train protecting apparatus comprising track apparatus relating to the making of a clear road for a train along a railway track, an unlocking device adapted to unlock said track apparatus, electromagnetic means adapted when energized to cause the unlocking operation of said unlocking device, a track contact on said track, a generator of electricity, a contacting device on said train, an electric circuit arranged partly on said train and partly on said track and adapted to be completed through said generator and through said electromagnetic means on contact of said contacting device with said track contact, indicating apparatus on said train, electromagnetic means on said train included in said circuit and adapted to prevent the operation of said indicating apparatus when energized by current of a predetermined normal value, and a resistance adapted to be connected in said circuit by said unlocking device when in its unlocking position and of such a value as to cause current of said predetermined normal value to flow through said electromagnetic means and thereby to prevent the operation of said indicating apparatus.

26. Train protecting apparatus comprising track apparatus relating to the making

- of a clear road for a train along a railway track, a locking device adapted to lock said track apparatus, electromagnetic means adapted when energized to cause the locking 5 operation of said locking device, a track contact on said track, a generator of electricity, a contacting device on said train, a normally open electric circuit arranged partly on said train and partly on said 10 track and adapted to be completed through said generator and through said electromagnetic means on contact of said contacting device with said track contact, indicating apparatus on said train, and electromagnetic means on said train adapted to cause the 15 operation of said indicating apparatus according to the flow of current therethrough, said locking device being adapted to control the said flow of current.
27. Train protecting apparatus comprising track apparatus relating to the making of a clear road for a train along a railway track, an unlocking device adapted to unlock said track apparatus, electromagnetic means 20 adapted when energized to cause the unlocking operation of said unlocking device, a track contact on said track, a generator of electricity, a contacting device on said train, a normally open electric circuit arranged partly on said train and partly on 25 said track and adapted to be completed through said generator, through said electromagnetic means on contact of said contacting device with said track contact, indicating apparatus on said train, and electromagnetic means on said train adapted to cause the 30 operation of said indicating apparatus according to the flow of current therethrough, said unlocking device being adapted to control the said flow of current.
28. Train protecting apparatus comprising track apparatus relating to the making of a clear road for a train along a railway track, a locking device adapted to lock said track 35 apparatus, electromagnetic means adapted when energized to cause the locking operation of said locking device, a track contact on said track, a generator of electricity, a contacting device on said train, an electric 40 circuit arranged partly on said train and partly on said track and adapted to be completed through said generator, through the track rails on opposite sides of a section of track, and through a resistance device, on 45 contact of said contacting device with said track contact, said resistance device including said electromagnetic means, and being adapted to allow the flow through the train portion of said circuit of current of predetermined normal value, but being adapted to be 50 short-circuited by a train standing on the rails of said section, indicating apparatus on said train constantly tending to operate but normally under a restraint adapted to be removed on contact of said contacting device with said track contact, and electromagnetic means on said train included in said circuit and adapted when energized by the flow therethrough of current of said predetermined normal value to restrain the operation 55 of said indicating apparatus.
29. Train protecting apparatus comprising track apparatus relating to the making of a clear road for a train along a railway track, an unlocking device adapted to unlock said track apparatus, electromagnetic means 60 adapted when energized to cause the unlocking operation of said unlocking device, a track contact on said track, a generator of electricity, a contacting device on said train, an electric circuit arranged partly on said train and partly on said track and adapted to be completed through said generator, through the track rails on opposite sides of a section of track, and through a resistance device, on 65 contact of said contacting device with said track contact, said resistance device including said electromagnetic means, and being adapted to allow the flow through the train portion of said circuit of current of predetermined normal value, but being adapted to be 70 short-circuited by a train standing on the rails of said section, indicating apparatus on said train constantly tending to operate but normally under a restraint adapted to be removed on contact of said contacting device with said track contact, and electromagnetic means on said train included in said circuit and adapted when energized by the flow therethrough of current of said predetermined normal value to restrain the operation 75 of said indicating apparatus.
30. Train protecting apparatus comprising track apparatus with means adapted to operate the same from a moving train, and means adapted to be operated from a track 80 station and to be thereby caused to effect the operation of said track apparatus and to prevent said track apparatus from being operated from said moving train.

Dated this twenty-seventh day of January
one thousand nine hundred and twelve.

ARTHUR REGINALD ANGUS.
